Primary Examiner — Karen E Kearney(74) *Attorney, Agent, or Firm* — Douglas L. Weller(57) **CLAIM**

The ornamental design for a USB memory device, as shown and described.

DESCRIPTION

FIG. 1 is a top plan view of the USB memory device.

FIG. 2 is a left elevational view of the USB memory device, the right being a mirror image of the left.

FIG. 3 is a bottom plan view of the USB memory device.

FIG. 4 is a front elevational view of the USB memory device.

FIG. 5 is a top front left perspective view of the USB memory device.

FIG. 6 is a left elevational view of the USB memory device with the USB connector cover open to 135 degrees to expose the USB connector; and,

FIG. 7 is a top front left perspective view of the USB memory device with the USB connector cover open to 135 degrees to expose the USB connector.
